UNITED STATES PATENT OFFICE

WILLIAM F. G. SWANN, OF SWARTHMORE, PENNSYLVANIA

MERCURY SPARK GAP

Application filed December 5, 1929. Serial No. 411,969.

The present invention relates to mercury spark gaps generally used for the production of high frequency oscillations and particularly refers to improvements in the structure thereof.

The principal object of the invention is to construct a mercury spark gap in a hollow evacuated vessel of improved form which is more rugged and durable than those made in accordance with constructions of the prior art.

A further object is to provide a construction of a spark gap which will withstand the severe strain of continuous operation and of atmospheric pressure.

Other objects and advantages of the invention will appear more fully hereinafter from the following detailed description together with the drawings, in which:

Fig. 1 is a vertical sectional view of the device; and

Fig. 2 is a plan sectional view taken on the line 2—2 of Fig. 1.

The device comprises a hollow spherical vessel 1 made of refractory glass or of any other suitable refractory material, having integral therewith a short hollow cylindrical portion 10. Extending from the cylindrical portion upwardly into the spherical chamber 2 is a member 3 which is made integral with the walls of the vessel. The member comprises a tubular neck portion having a concavo-convex head, the convex sides of which may be substantially parallel to the walls of the chamber 2. The concave portion is provided for the reception of a quantity of mercury indicated at 5 which is permitted to flow down into the tubular portion by means of the canal 12 so that the mercury may come in contact with a terminal 7. The convex sides of the member 3 also form a mercury-receiving space with the walls of the chamber 2 and it extends down into the cylindrical portion 10, as indicated at 11, so as to permit the mercury indicated at 4 to come into con-

tact with another terminal 6. It will be seen that the mercury-receiving space of the chamber 2 is insulatingly separated from the concave mercury-receiving space by means of the rounded portion 13 of the member 3, thus forming an electrical gap between the mercury at 4 and 5 which may be traversed by a spark when an electric current is introduced at the terminals 6 and 7. The chamber 2 is evacuated at the point 8 and sealed. The body 1 is made spherical so as to enable it to resist strains arising from atmospheric pressure.

In the preferred embodiment of my invention, the member 3 is also hollow and may be evacuated at the point 9, although it may be made of solid refractory glass integral with the body portion 1 if desired, without departing from the scope of the invention. The provision of the member 3, which is the novel feature of the invention, is to provide a means by which the two portions of mercury may be insulated from each other without departing from an external spherical shape of the apparatus. Moreover, the construction is such that the weight of the mercury will not easily break the glass, and such that the neck portion of the vessel will be insulated from the high heat which is present at the portion 13 when the spark gap is in operation, which heat also tends to break the glass. The evacuation of the member 3 contributes to the strength of the entire vessel since there is no appreciable difference of pressure between the chamber 2 and the inside of the member 3. The spark gaps of the prior art generally comprise a conical evacuated glass vessel with a mercury-receiving space in the base portion of the vessel, and the necessity of separating the two portions of the mercury results in an external form which is weak as regards support of the mercury and the strain of external atmospheric pressure. Such devices can seldom be used, for more than three minutes of continuous operation, while the

device of my invention has been successfully operated continuously for more than four hours without showing any signs of the glass vessel cracking or tending to break. The ability of the device to withstand the great strain of continuous operation renders it serviceable where it is desired to maintain a mercury spark for long periods of time, which had been heretofore impossible.

10 While I have shown only one embodiment of my invention, for purposes of illustration and description, it is obvious that other changes and modifications may be made without departing from the scope thereof and I, 15 therefore, desire to be limited only by the scope of the appended claims.

I claim:

1. A device of the class described comprising a spherical chamber, and a second chamber supported within and from the walls of said first chamber combining with said walls to provide a mercury-receiving space, said second chamber having a recessed portion to provide another mercury-receiving space so as to form a gap when said spaces are filled with mercury.

2. A mercury spark gap comprising an evacuated spherical chamber, and an evacuated member supported within and from the walls of the chamber combining with said walls to provide a mercury-receiving space, said member having a concave portion to provide another mercury-receiving space so as to form a gap when said spaces are filled with mercury.

3. A mercury spark gap comprising an evacuated spherical chamber, and an evacuated member supported within and from the walls of the chamber combining with said walls to provide an outer annular mercury-receiving space underlying the external surface of the member, said member having a concave portion to provide an inner mercury-receiving space so as to form an annular gap when said spaces are filled with mercury.

4. A device of the class described comprising an evacuated spherical chamber having a cylindrical portion, and a hollow evacuated member supported within and from the walls of the cylindrical portion of the chamber and extending into said chamber to provide an outer annular mercury-receiving space underlying the external surface of the member, said member having a concave portion at its upper end to provide an inner mercury-receiving space so as to form an annular gap when said spaces are filled with mercury.

5. A device of the class described comprising a hollow evacuated member having a spherical head and a cylindrical neck, another hollow evacuated member having a concavo-convex head and a cylindrical neck disposed within said first member with its concavity extending upwardly into the spherical chamber of said first member and

its convex surface disposed in substantially parallel relation therewith to provide a mercury-receiving space, and a terminal extending from the space through the wall of said first member, said second member having means communicating with the concave portion downwardly to another terminal so that an annular spark gap is formed when said concavity and said space are filled with mercury.
